US00D934237S

(12) **United States Design Patent** (10) **Patent No.:** **US D934,237 S**
(45) **Date of Patent:** **** Oct. 26, 2021**

(54) **PORTABLE ELECTRONIC DEVICE**

(71) Applicant: **NTT DOCOMO, INC.**, Chiyoda-ku (JP)

(72) Inventors: **Eriko Yoshida**, Chiyoda-ku (JP); **Katsuyuki Takama**, Chiyoda-ku (JP); **Tetsu Miyazawa**, Minato-ku (JP); **Kazushige Miyake**, Kawasaki (JP)

(73) Assignee: **NTT DOCOMO, INC.**, Chiyoda-ku (JP)

(**) Term: **15 Years**

(21) Appl. No.: **29/659,217**

(22) Filed: **Aug. 7, 2018**

(30) **Foreign Application Priority Data**

May 10, 2018 (JP) 2018-010176

(51) **LOC (13) Cl.** **14-02**

(52) **U.S. Cl.**

USPC **D14/341**

(58) **Field of Classification Search**

USPC .... D14/138 AA, 138 AB, 138 AC, 138 AD, D14/138 C, 138 G, 218, 248, 315-318, D14/341-347, 371, 374; D6/308, 310; D10/30, 50, 65, 104.1; D18/6-7;

D19/26, 59-60; D21/324, 329-330, 332

CPC ... H04M 1/0202; H04M 1/0266; H04M 1/725

See application file for complete search history.

(57) **CLAIM**

The ornamental design for a portable electronic device, as shown and described.

DESCRIPTION

FIG. 1 is a front, bottom, and right side perspective view of a portable electronic device;

FIG. 2 is a rear, top, and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

1 Claim, 8 Drawing Sheets
